(57) **CLAIM**

The ornamental design for an ice barrier for drinking vessels, as shown and described.

DESCRIPTION

1.-9. Ice barrier for drinking vessels

1.1 : Perspective

1.2 : Front

1.3 : Right

1.4 :Top

1.5 : Enlarged

A thin ice barrier that slots onto the rim of a drinking vessel, holding the ice and other solids back from the drinker's mouth, thus enabling easier drinking of the liquid; also effective for other solids in a hot drink.
